STRAIN RELEASE FOR WRINGERS

Earl H. Erdman, Salem, Ohio, assignor to Mullins Manufacturing Corporation, Salem, Ohio, a corporation of New York

Application June 11, 1934, Serial No. 729,977

6 Claims. (Cl. 108—32)

The object of my invention is to produce a wringer wherein the normal working pressure maintained between the coacting rollers may be surely and quickly released by the operator in case of need.

The accompanying drawings illustrate my invention.

Fig. 1 is a front elevation in partial vertical medial section;

10 Fig. 2 is a fragmentary elevation of one end of the structure, showing the releasable latching means;

Fig. 3 is a fragmentary section on line 3—3 of Fig. 1;

15 Fig. 4 is a front elevation, in partial vertical medial section, of a modification, and

Fig. 5 is a fragmentary end elevation of the modification shown in Fig. 4.

In the drawings 10 indicates the main base frame of the wringer, this frame comprising channelled end stiles 11, 11' within which the usual bearing blocks 12 and 13 for the rollers 14 and 15 respectively, are slidably mounted.

The upper ends of the stiles are open, to permit ready withdrawal of the rollers and bearing blocks.

Coacting with the upper ends of the stiles 11, 11' is a channelled crosshead 16 within which is arranged the pressure spring 17 adapted to engage the upper bearing blocks 13, said spring, at its middle, engaging the adjustable abutment screw 18.

The outer face of the stile 11 is provided near its upper end, with a projection 20 beneath which a portion 21 of crosshead 16 may be hooked, and from which said portion may be readily separated by an upward swing of the opposite end of the crosshead.

The outer face of the stile 11 is provided near its upper end with an outwardly-projecting pin 25 and the adjacent end of crosshead 16 is provided with a headed pin 26 upon which are journaled the two latches 27 and 28, each of which comprises a depending arm notched at its inner end as indicated at 29, and with an upper arm notched at 30 on its inner edge to form a finger 31.

The weight of the lower end of each arm 27 and 28 is greater than the weight of the upper end so that gravity will serve to normally urge the two arms 27 and 28 to the relative positions shown in Fig. 2, and in these positions the adjacent ends of the fingers 31, 31 are separated by an amount equal to the width of a comparatively thin blocking finger 35 which is carried by a rocker-arm 36 which straddles one end of cross-

head 16. The opposite end of head 16 is straddled by a similar rocker-arm 36' (lacking finger 35) and the two rocker arms are connected into a unitary rockable structure by channelled bars 36", 36'". The rocker-arm structure 5 is yieldingly held on head 16 by headed pins 31, 37 which are passed through arms 36, 36' and crosshead 16 and are each yieldingly held in place by a light spring 38 which, at its inner end, abuts an abutment 39 carried by pin 37. 10

In the form shown in Figs. 4 and 5 finger 35 is carried by a plate 36" having a yoke 40 which carries an upwardly-projecting arm 41 upon the upper end of which is secured a manipulating head 42 which is preferably of soft rubber or 15 other similar material which may be struck a considerable blow by the hand of an operator without injuring the hand.

In order to prevent head 16 from being projected entirely free from the base, when finger 20 35 is withdrawn from between latches 27 and 28, the construction shown in detail in Fig. 3 has been found desirable.

A U-shaped clip 45 straddles bearing block 13 in standards 11 and 11' and at the roots of its arms 46 is provided with outwardly-projecting fingers 47, 47 which rest upon inwardly-projecting fingers 48, 48 carried by the upper ends of the front and rear walls of standards 11 and 11'. 30

Each arm 46 is provided with an outwardly-projecting lip 49 which underlies one of fingers 48 and is normally spaced some distance below the plane of fingers 48, as shown. The ends of spring 17 underlie the bases of clips 45. 35

When cross head 16 is released and projected upwardly by spring 17, lips 49 rise into engagement with fingers 48. To fully release cross-head 16 arms 46 may be sprung toward each other enough to permit lips 49 to clear fingers 48. 40

In operation (referring to Figs. 1 and 2), the left-hand end of crosshead 16 having its portion 21 hooked under projection 20, the operator grasping head 16 and one of bars 36" will withdraw finger 35 from between fingers 31 and will urge the right-hand end of the crosshead downwardly over the upper end of stile 11 to bring the lower ends of latches 27 and 28 to underlie pin 25, whereupon release of the lateral pressure upon bar 36" finger 35 will move down between 50 fingers 31, 31 to block swinging movement of the latches 27 and 28, so that the right-hand end of the crosshead will thereby be locked in operative position.

Slight pressure upon either bar 36" will rock 55

arms 36, 36' to tilt finger 35 from between fingers 31 so that the upward force of spring 17 cams the latch fingers 27 and 28 away from pin 25.

Referring now to the form shown in Figs. 4 and 5.

Whenever it is desired to release the pressure of spring 17 upon the upper roller 15 the operator has merely to stroke head 42 from any direction so as to tilt finger 35. Tilting in one direction will withdraw said finger upwardly from between fingers 31; in another direction will depress finger 35 into notches 30; and canting of finger 35 between fingers 31, to one side or the other, will serve to decentralize the finger 35 relative to fingers 31 so that the camming effect induced by spring 17 upon pin 25 through the lower sides of the notches 29 will serve to force the lower ends of the latches 27 and 28 away from each other, the fingers 31 pinching the canted finger 35 between themselves. In any event, dislocation of finger 35 from its critical blocking position between fingers 31 will permit withdrawal of the lower ends of the latches 27, 28 from pin 25, and consequent release of the right-hand end of the crosshead 16.

It will be noted that the connection between arm 36 and crosshead 16 is a sort of universal joint, the construction being such that displacement of head 42 by a force supplied from any direction will serve to so dislocate finger 35 relative to fingers 31 that it is no longer capable of successfully blocking outward swing of the lower ends of the latches 27 and 28.

I claim as my invention:

35. 1. In a wringer, the combination with a roller-supporting base and an associated crosshead, vertically-interlocking means carried by the base and one end of the cross head, and releasable latching means interposed between the other end 40 of the crosshead and the base, said latching means comprising a pair of cooperating latches pivoted upon the crosshead on a substantially horizontal axis, a pin carried by the base in position to be underlaid by the latches, a blocking-finger interposable between the latches to maintain pin engagement thereof, and an element associated with said last-mentioned finger by which said finger may be retracted from blocking position.

2. A wringer of the character specified in claim 1 wherein the blocking-finger is carried by a rocker structure rockably mounted upon the crosshead and having manipulating portions extending lengthwise of the crosshead.

3. A wringer construction of the character specified in claim 1 wherein the blocking finger is carried by a plate mounted upon the crosshead and tilttable thereon.

4. In a wringer comprising a base frame element and a crosshead frame element, vertically-interlockable means carried by the base frame element and the crosshead frame element at adjacent ends, and releasable latching means arranged at the opposite end of said frame members and comprising a pair of coacting latch levers pivotally mounted upon one of the frame members, a coacting pin carried by the other frame member in position to be straddled and vertically overlapped by the latch levers, a latch-lever 20 blocking-finger carried by one of the frame members, and means movably mounted upon one of the frame members and associated with said blocking-finger whereby it may be retracted from blocking position relative to the latch levers. 25

5. In a wringer, a base having a hollow end standard open at its upper end, a vertically-reciprocable bearing-block mounted therein, and an inverted U-shaped restraining clip comprising a pair of spring arms straddling said block, said 30 clip having portions restable upon the base standard and outwardly projecting portions carried by the spring arms and spaced normally below and out of contact with and vertically interlockable with portions carried by the base standard. 35

6. In a wringer, the combination with a crosshead frame element, of a latch release comprising a pair of inverted U-shaped elements saddled upon the opposite ends of the crosshead and connected by bars paralleling the crosshead, two 40 pins, one projecting through each U-shaped element and the crosshead, two springs, one associated with each pin and yieldingly acting upon its pin axially, and a pair of pivoted latch elements normally blockable by a portion carried 45 by one of said U-shaped elements.

EARL H. ERDMAN.
